(57) CLAIM

I claim the ornamental design for an ornamental Christmas decoration, shown and described.

DESCRIPTION

FIG. 1 is a left front perspective view of an ornamental Christmas decoration showing my design;

FIG. 2 is a front view of FIG. 1;

FIG. 3 is a rear view of FIG. 1;

FIG. 4 is a top plan view of FIG. 1; and,

FIG. 5 is a right side view of FIG. 1.

1 Claim, 5 Drawing Sheets
